CLAIM

The ornamental design for a biometric sensor, as shown and described.

DESCRIPTION

FIG. 1 is a bottom view of the biometric sensor;
FIG. 2 is a bottom perspective view of the biometric sensor;
FIG. 3 is a left side view of the biometric sensor;
FIG. 4 is a right side view of the biometric sensor;
FIG. 5 is a top view of the biometric sensor;
FIG. 6 is an upper side of the biometric sensor; and,
FIG. 7 is a lower side of the biometric sensor.
